UNITED STATES PATENT OFFICE.

THOMAS JEFFERSON CROOK, OF WICHITA, KANSAS.

HYDROCARBON-BURNER.

1,238,003.

Specification of Letters Patent. Patented Aug. 21, 1917.

Application filed January 24, 1916, Serial No. 73,846. Renewed July 17, 1917. Serial No. 181,174.

To all whom it may concern:

Be it known that I, THOMAS JEFFERSON CROOK, a citizen of the United States of America, residing at Wichita, in the county 5 of Sedgwick and State of Kansas, have invented certain new and useful Improvements in Hydrocarbon-Burners, of which the following is a specification.

My invention relates to improvements in 10 hydrocarbon burners.

The primary object of the invention is to provide a burner in which the burner-head, mixing chamber and retort or generator are relatively disposed to insure a perfect 15 commingling of the hydrocarbon and air, and a resultant combustion which is practically invisible, devoid of any odor, and which wholly eliminates the deposit of soot upon the walls of the burner-head.

20 Other objects of the invention are to provide a burner which is highly efficient and at the same time extremely simple in construction and arrangement, particular regard being had to the facility with which the 25 constituent parts of the device may be set up and dismantled; and to provide a burner-head and a mixing chamber as a unitary structure.

To the accomplishment of the recited objects and others coördinate therewith, the preferred embodiment of my invention resides in the construction and arrangement hereinafter described, illustrated in the accompanying drawings and embraced within 35 the scope of the appended claims.

In said drawings—

Figure 1 is a perspective view of the hydrocarbon burner embodying my invention.

Fig. 2 is an end elevation of the burner.

40 Fig. 3 is a longitudinal sectional view of the device.

Fig. 4 is a transverse sectional view taken along lines 4—4 of Fig. 3.

Fig. 5 is a transverse section taken along 45 lines 5—5 of Fig. 3, and

Fig. 6 is a top plan view of a modified form of my invention.

Opposed to the theory that a high degree of heat is essential in producing a proper 50 mixture of hydrocarbon and air, I have discovered as a result of experiments extending

over a period of several years, that only a fair degree of heat will insure, by far, more satisfactory combustion. The tests which I have conducted showed conclusively that 55 when hydrocarbon and air are preliminarily subjected to intense heat, the component particles of the major portion of the hydrocarbon becomes disassociated and lose their identity as a medium capable of combining 60 with air to form a true combustible mixture in the sense of what is desired in hydrocarbon burners. The presence of these disassociated particles together with the particles which escape the decomposing influence of 65 the intense heat, produces a yellow flame, a disagreeable odor, and deposits of soot upon the walls of the burner head. I have entirely eliminated these disadvantages by arranging the parts of the burner so that the 70 mixing chamber and retort will only be heated to a point which will positively insure the proper mixing of the hydrocarbon and air.

Generally, my invention comprises a drip pan having a plurality of uprights designed 75 to support a side retort, the burner head or burner heads, as the case may be, occupying a nested position with respect to this retort, and the mixing chamber being formed as an integral part of the head or heads with depending air inlets arranged upon its opposite sides and the delivery end of said retort discharging from beneath and centrally of 80 the mixing chamber. While the principles involved in my invention are applicable to a 85 single burner head or burner cap, I prefer for present purposes the adaptation of the principles to one of the multiple type. In conjunction with this particular form of the invention I take an elongated tubular like body closed at both ends and intercept its length, preferably at the middle, so as to form a pair of burner heads, this central portion also serving as a mixing chamber for the hydrocarbon and air. Each burner tube 90 is preferably polygonal in cross section and has its opposite sides provided with equidistant vertical kerfs, the portions of the burner heads between the adjacent terminals of the kerfs being imperforate. These kerfs 95 obviously serve as flame openings, and toward their bases they are arranged in juxta-

position to a side retort, which as previously set forth, is sustained by the uprights projecting from the drip pan. This relative disposition of the flame openings and 5 retort preclude the possibility of the hydrocarbon becoming too hot. The air inlets are disposed in the cut away portions and in immediate proximity to the adjacent terminals of the burner heads whereby it will be 10 seen that the air is preliminarily heated so that by the time it enters the mixing chamber it is in a very receptive condition for combining with the hydrocarbon. However, it should be understood that the air inlets 15 are not surrounded totally by the burner heads, but that they are simply inclosed by portions of the adjacent terminals of the burner heads so that too high a degree of heat will not obtain. Considering conjunc- 20 tively, the arrangement of the retort and mixing chamber, both the hydrocarbon and air are preliminarily treated so that the resultant vapor will represent a perfect mixture, which will be uniformly distributed 25 throughout the longitudinal extent of the burner heads.

In the drawings, 1 designates the drip pan having a plurality of uprights 2 with upper rabbeted terminals 3, upon which 30 rests the retort pipe 4. Occupying a nested position with respect to this retort is a tubular-like structure 5 octagonal in cross section and having its length intercepted at the center by a vertically disposed mixing 35 chamber 6. By virtue of forming the mixing chamber medially of the extent of the tubular-like structure 5 I am enabled to secure a pair of aligned, elongated burner heads 7 and 8, each of the said burner heads 40 being closed at its outer end and provided with a plurality of equi-distant kerfs 9 ex- 45 tends vertically upon opposite sides with imperforate top and bottom portions 10 and 11. These kerfs 9 constitute flame open- 50 ings, and the nested relation of the retort and the burner heads is such that only that portion of the flame emitted from the lower plane of the kerfs plays upon the said retort. It is this arrangement that insures a 55 proper preliminary heating of the hydro- 60 carbon, that is to say, that the component particles and the hydrocarbon are not dis- 65 sociated nor "cracked", which result would obtain if the retort were located in a higher 70 plane with respect to the flame opening and manifestly in the zone of considerably more heat. The proximal end 12 of the retort 75 terminates at a point midway of the mixing chamber, where it is deflected down- 80 wardly and then upwardly so as its tip or nipple 13 will register with the opening 14 in the base of the mixing chamber 6.

The mixing chamber comprises a central 85 passage 15 flanked by a pair of secondary

passages 16, the central passage and the two 65 side passages communicating through the medium of a supplemental chamber 17, which occupies a superposed position with respect thereto and serves as a baffle to deflect the gaseous vapor downwardly through 70 the side passages and the openings 18 into the respective burner heads 7 and 8. Any suitable closure as 19 may be employed in conjunction with the top of the supplemental chamber 17. 75

As will be found upon inspection of Fig. 1 of the drawing, each of the burner heads terminates short of the mixing chamber 6, thereby leaving a recess or cutaway portion 20 upon diametrically opposite sides of the 80 chamber. I utilize these cutaway portions as an extremely desirable location for the air intake pipes 21, which project a short distance outwardly and then extend downwardly to a point above the base of the drip pan 1. By reason of arranging the intakes in this manner it will be seen that they are only in the zone of heat influence which is bounded by a portion of each of the adjacent ends of the burner-heads, and it follows that as the air enters through the intakes 21 it will not be heated except only to such degree as has been found desirable and obviously best for commingling with the hydrocarbon which issues in atomized form 90 from the tip 13 into the central passage 15 of the mixing chamber. 95

In Fig. 6, I have shown a slightly modified form of my invention, wherein a circular burner-head 22 is combined with the same type of mixing chamber, as previously described. In this instance I employ a short connection as 23 between each of the 100 passages 16 and the burner-head. In all other respects, the construction and operation of this particular form is the same as that shown in Figs. 1 to 5 of the drawings. 105

In operation, the hydrocarbon under pressure is supplied to the retort 4, and in traversing the extent of this pipe it is subjected to an initial heating so that when atomized in the central passage 15 of the mixing chamber it is in the best possible condition for combining with the air entering through intakes 21. As previously set forth, the air, too, has by this time been heated to the proper temperature owing to the proximity of the intakes to the portions of the adjacent terminals of the burner-heads. The admixture rises through the central passage 15 and very rapidly forms into a gaseous vapor so that by the time it issues through the openings 18 at the bottom of passages 16 it will be in ideal condition for burning. Such an arrangement of the retort, the mixing chamber and burner-head eliminates the possibility of the constituent particles of the hydrocarbon from be- 110 115 120 125

coming overheated and the disadvantages which obtain under such circumstances, namely the production of a yellow flame, which is invariably devoid of the proper heat units, the production of a very disagreeable odor, and the formation of quantities of soot upon the walls of the burner-head.

It should be understood that in its broader aspects my invention comprehends not only the employment of the various means shown and described, but all equivalent means for performing the recited functions. It is desired to reserve the right to effect such variations and modification of the device as may come fairly within the scope of the appended claims.

What I claim is:

1. In a hydrocarbon burner, a plurality of supports, a retort mounted upon said supports, a pair of burner heads and a mixing chamber arranged centrally of said burner-heads, said mixing chamber communicating with the retort and the burner heads, said burner heads and said mixing chamber constituting a unitary structure resting upon the retort and adapted to be lifted bodily therefrom.

2. In a hydrocarbon burner, the combination of an equilateral polygonal burner head, a retort supporting said burner-head, and a mixing chamber communicating with the retort and the burner head, said burner head being provided with a plurality of kerfs upon opposite sides extending above and below said retort, and solid portions between the adjacent terminals of the kerfs.

3. In a hydrocarbon burner, the combination of a horizontal equilateral polygonal burner head, a retort supporting said burner-head, and a mixing chamber communicating with the retort and the burner head, said burner-head being provided with a plurality of kerfs upon opposite sides extending above and below said retort, the major portion of the vertical extent of the kerfs lying above the retort.

4. In a hydrocarbon burner, the combination of a pair of elongated horizontally arranged burner heads, a retort, and a mixing chamber arranged between the burner heads and having one upwardly extending passage and a pair of downwardly extending passages, said upwardly extending passage having an air inlet, while said downwardly extending passages open into said burner-heads, and said retort having its discharge end connected to said upwardly extending passage.

5. In a hydrocarbon burner, the combination of a pair of burner heads, a retort, and a mixing chamber arranged between the burner-heads and partitioned to form a central passage and a pair of passages commu-

nicating with and disposed upon opposite sides of the central passage, said central passage having an air inlet, while said pair of passages open into said burner-heads, and said retort having its discharge end connected to said central passage.

6. In a hydrocarbon burner, the combination of a pair of aligned elongated burner-heads, a mixing chamber common to said burner-heads, and having air inlet means, and a retort partially surrounding the burner-heads and projecting within the mixing chamber and above the bottom of the burner-heads.

7. In a hydrocarbon burner, the combination of a mixing chamber having a central intake passage and a pair of outlet passages parallel to and communicating at one end with said intake passage, a burner-head adapted to receive the mixture delivered from each outlet passage, a retort lying in contact with said burner heads throughout its length and adapted to discharge into said passage, and means for admitting air to said intake passage.

8. In a hydrocarbon burner, the combination of a pair of burner heads, a mixing chamber common to said burner heads, depending air inlet pipes arranged upon opposite sides of said chamber, and a retort partially surrounding the burner heads and adapted to discharge into said mixing chamber.

9. In a hydrocarbon burner, the combination of a mixing chamber having air inlet means, a pair of elongated burner heads arranged at right angles to and upon diametrically opposite sides of said chamber, and communicating therewith, and a side retort adapted to discharge into said mixing chamber, said mixing chamber extending above the top of the burner-heads.

10. In a hydrocarbon burner, the combination of an elongated tubular structure closed at both ends, said structure having transverse partitions to form a mixing chamber intercepting the length of said structure, and slotted to form a pair of burner heads, said partitions having apertures to establish communication with the burner-heads and said mixing chamber, and a retort adapted to discharge into said mixing chamber.

11. In a hydrocarbon burner, the combination of an elongated tubular-like structure closed at both ends, the medial portion of said structure being cut away upon opposite sides to form a pair of burner heads, a mixing chamber between said cut away portions communicating with said burner heads, and a retort adapted to discharge into said mixing chamber.

12. In a hydrocarbon burner, the combination of an elongated tubular-like structure closed at both ends, the medial portion of

4
said structure being cut away upon opposite sides to form a pair of burner heads, a mixing chamber between said cut away portions communicating with the burner heads, air intake means depending from the mixing chamber, and a retort adapted to discharge into said mixing chamber.

Copies of this patent may be obtained for five cents each, by addressing the "Commissioner of Patents, Washington, D. C."

In testimony whereof I affix my signature in the presence of two witnesses.
